PINHOLDER

Ogden N. Pratt, Dayton, Ohio

Application January 5, 1952, Serial No. 265,183

11 Claims. (Cl. 1—46)

1

This invention relates to pin holders suitable for commercial and domestic use where the basting of fabric materials requires the use of many pins.

The primary object of the invention is to provide an improved pin holder which includes mechanical means for feeding and positioning the pins during basting operations.

A specific object of the invention is to provide a pin holder with an automatic feed means for advancing pins to an ejection position, and a manually operable means to manipulate a pin from that position into a position suitable for insertion into fabrics during basting or similar operations.

A further object of the invention is to provide an improved pin holder of simple construction which is readily operable by one hand of the worker during basting of fabrics or in other types of operations requiring the use of a plurality of pins.

Another object of the invention is to provide an improved pin holder which, due to its few parts, is susceptible to inexpensive manufacture.

With the foregoing, and other objects in view, the invention resides in the following specification and appended claims, certain embodiments thereof being shown in the accompanying drawings, in which:

Fig. 1 is a partially sectioned view in perspective of the invention;

Fig. 2 is a partially sectioned end elevational view of the invention;

Fig. 3 is a partial view in perspective of the ejection end of the invention;

Fig. 4 is a sectional plan view of the body portion only of the invention taken along the line 4—4 of Figure 1; and

Fig. 5 is a rear elevational view of the invention.

Referring more particularly to the drawings, the pin holder referred to generally at 1 consists of two main parts, a body 2 and an ejector plate 3. The body 2 is preferably formed by die casting a plastic material such as Bakelite; however, it is obvious that other materials such as metal would be equally suitable. The body 2 is provided with an opening 4, the purpose of which will hereinafter be described. Adjacent the opening 4 on either side of the body 2 are bosses 5 having underlying arcuate grooves 6. The body 2 is formed with a longitudinal slot 7 running from the loading end 8 to the ejection end surface 9 where it is joined by a transverse slot 10 in the body 2. The slot 7 is of such design as

2

to accommodate a plurality of pins 11 in side-by-side arrangement with their flat heads being received in the circular channel portion 12. It is to be noted that the slot 7 is formed on both sides of the opening 4 so that the upper and lower sections of pins 11 are held against lateral movement with respect to the body 2 when they are inserted at the loading end 8.

A resilient means, preferably a heavy rubber band 13, is used to automatically move the pins 11 toward the end surface 9 after a leading pin is ejected from the body. This band 13 is first engaged with one of the grooves 6 in a boss 5 after the body has been loaded with pins. It is then passed around the last pin 14 through the opening 4 and looped over the other boss 5 to engage the other groove 6. Thus, as can clearly be seen in Fig. 4, a considerable amount of force may be applied to the pins to move them toward the left, or the ejecting position.

The length of the channel 7 and the position of the bosses 5 as well as the strength and length of the band 13 will determine the amount of pins to be effectively accommodated by this pin holder. Thus the body 2 may be longer to accommodate more pins. The bosses 5 may be located further to the left when viewing Fig. 4 so that less pins will be left in a dormant position between the points 15 and 16 in the body 2 when the band 13 has advanced pin 14 to the point 16.

The body 2 is formed with an elongated arcuate portion 17 which consists of a substantially circular head 18 joined to the body 2 by neck portion 19. The neck portion 19 defines a recess 20 between the shoulder 21 of the body 2 and the head 18. The neck portion 19 also defines the inner surface of a groove 22 on the right-side of the body as viewed in Fig. 2. The outer surface of the groove 22 is defined by the rib 23.

The ejector plate 3 is preferably formed from a single piece of metal having superior resilient qualities. The upper end of the plate 3 is formed to engage the head 18 of the elongated portion 17 of body 2. The end 24 of plate 3 is placed in groove 22 and the plate is then sprung over head 18 until the indented portion 25 is received in recess 20 of the body 2. It is to be noted that the arcuate portion 26 of the plate is spaced from the upper edges of head 18 for a purpose hereinafter described. It should also be noted that the indented portion 25 of the plate 3 occupies only a portion of the recess 20.

The plate 3 is provided at one side with an ejector member 27 extending transversely to plane defined by the plate. The member 27 is provided

with an inclined portion 28 for engaging the pins 11. The lower portion of the member 27 is recessed at 41 when the plate 3 is formed to provide an offset portion 29 which serves as a pin stop during operation of the mechanism. The end of the body 2 is recessed at 30 to accommodate this offset member 29 as seen in Fig. 3. The member 27 is provided with a slot 31 through which a pin 32 extends to limit the outward movement of the plate 3. The pin 32, as shown in Fig. 4, extends from the exterior of body 2 through the slot 31 of the plate, and the rear section 33 of slot 10 into the body at 34. This pin may be press-fitted into position or may have a threaded engagement at 34.

Adjacent to and leading into the section 33 of slot 10 is a cam surface 35 which is engaged by a similar cam surface 36 on member 27 during an operation of the device.

The complete operation of the invention will now be described. A plurality of pins, either in connected strip form or otherwise, are loaded into slot 7 at loading end 8. The first pin loaded abuts the surface 9 and the remainder fill the slot 7. The rubber band 13 is then looped over one boss 5 to engage a groove 6, and is then wrapped around the last pin 14 through opening 4 to engage the groove 6 in the other boss 5. The operator may then grasp the holder by placing the thumb against the body 2 and the fingers against the spring plate 3. Upon the application of pressure, the plate 3 is moved inwardly until cam surfaces 35 and 36 engage each other. Upon the engagement of these two surfaces, further pressure will move the plate 3 and consequently the member 27 inwardly and downwardly. The downward movement is permitted by the spaced relationship between the arcuate portion 26 of the plate and the upper edge of the head 18 as well as by the relative size of recess 20 to the indented portion 25 of the plate.

The angular portion 28 of member 27 engages a pin in the transverse slot 10 and will rotate the first pin about its head as an axis. As the pin is under the tension of resilient band 13, the depending pin stop member 29 which is provided on member 27, prevents the said pin from being projected out of the access opening 37 provided in the end of the casing. When the pin has been rotated to the position shown in Fig. 2, it will be seen that, due to the cam action of surfaces 35 and 36, the heel portion 38 of member 27 has moved downwardly over the head 39 of the pin to firmly engage the shank thereof at 40 the other side of the shank being firmly engaged against lower wall 43 of slot 10. The lower surface 42 of the member 27 at recess 41 then firmly engages the head 39 of the pin to hold it in the circular portion 12 of channel 7.

With the pin thus extending at right angles from the body a basting operation may be made. The fabric so engaged by the pin acts through friction to dislodge the pin from the holder after pressure on the spring plate 3 has been released and the member 27 has moved back to the normal position as shown in Figure 1; the holder 1 as a whole being moved longitudinally of the pin and in a general direction opposite to that used to insert the pin in the fabric.

Thus it is seen that the invention provides an improved holder and manipulator for pins which is simple in construction and which is easily handled when it is desired to place pins in fabrics undergoing basting operations.

I claim:

1. A pin holder comprising a body for carrying a plurality of pins, means connected to the body to feed said pins through said body to an ejecting station therein, and means connected to said body and operable in a plane transverse to the plane of said feed means for rotating said pins singly about one extremity of said pins as an axis from a feed position to an ejection position at said ejecting station.
2. A pin holder comprising a body for carrying a plurality of headed pins, means connected to the body to feed said pins through said body to an ejecting station therein, and means connected to said body and operable in a plane transverse to the plane of said feed means for rotating said pins singly about their heads as an axis from a feed position to an ejection position.
3. A pin holder comprising a body for carrying a plurality of headed pins, means connected to said body to feed said pins through said body to an ejecting station therein, and means connected to said body and operable at an angle to said feed means for rotating said pins singly about their heads as an axis from a feed position to an ejection position at said ejection station.
4. A pin holder comprising a body for carrying a plurality of headed pins, resilient means to feed said pins through said body to an ejecting station therein, and a plate means attached to said body for relative movement thereto in a plane transverse to the plane of said feed means to rotate said pins singly about their heads as an axis from a feed position to an ejection position at said ejection station.
5. A pin holder comprising a body for carrying a plurality of headed pins, said body including a longitudinal slot with a circular portion at the lower extremity thereof to accommodate the heads of the pins, resilient means to feed said pins through the longitudinal slot in said body to an ejecting station comprising a transverse slot in said body, and plate means attached to said body for relative movement thereto in the transverse slot, the said plate means being operable to rotate a pin about its head as an axis from the feed position in the longitudinal slot to the ejection position in the transverse slot and to cooperate with the circular portion of the longitudinal slot and the lower wall of the transverse slot in firmly holding said pin in said ejection position until said plate is returned to its non-operating position.
6. A pin holder comprising a body with longitudinal and transverse slots therein, the longitudinal slot accommodating a plurality of pins, resilient means to feed said pins through the longitudinal slot in said body to an ejecting station therein, a resilient plate means attached to said body for relative movement thereto in a plane transverse to the plane of said feed means cooperating with the transverse slot, said plate being normally biased by its own resiliency to a nonoperating position and being operable under pressure to rotate a pin from the feed position to the ejection position.
7. A pin holder comprising a body with longitudinal and transverse slots therein, the longitudinal slot accommodating a plurality of pins, each pin having a head portion and a shank portion terminating in a point, resilient means to feed said pins through the longitudinal slot in said body to an ejecting station therein, and means cooperating with the transverse slot and

attached to said body for relative movement thereto in a plane angular to the plane of the feed means to rotate a pin at the ejecting station about its head as an axis from the feed position to the ejection position so that a substantial portion of the pointed shank of the pin is made to protrude from the body.

8. A pin holder comprising a body for carrying a plurality of pins, each pin having a head portion and a shank portion terminating in a point, resilient means to feed said pins through said body to an ejecting station therein, and a resilient plate means attached to said body for relative movement thereto in a plane transverse to the plane of the feed means, said plate being normally biased by its own resiliency to a non-operating position and being operable under pressure to rotate a pin about its head as an axis so that a substantial portion of the shank of the pin is made to protrude from the body.

9. A pin holder for use in basting and other pinning operations comprising a body having a slot extending longitudinally from one end thereof through the body and connecting to a transverse slot adjacent the other end of the body, the longitudinal slot being adapted to hold a plurality of headed pins in side-by-side relationship, resilient means attached to said body to move said pins through said longitudinal slot to said transverse slot in the body, and a resilient plate attached to said body for relative movement thereto in a plane transverse to the plane of the longitudinal slot in the body, the said plate having a depending ejecting member extending into the transverse slot of the body so that, upon application of pressure to said plate, the depending ejecting member will engage a pin in the feed position and rotate said pin about its head as an axis to the ejection position in the transverse slot.

10. A pin holder for use in basting and other pinning operations, comprising a body with a longitudinal slot including a circular lower portion extending from one end thereof, and terminating in a transverse slot therethrough for carrying a plurality of pins, said transverse slot having a lower wall, each pin having a circular head portion of slightly less diameter than the circular portion of the longitudinal slot and having a shank portion terminating in a point, resilient means to feed said pins through the longitudinal slot in said body to an ejecting station at the transverse slot in the body, a resilient plate means attached to said body for relative movement thereto and being normally biased by its

own resiliency to a non-operating position, a cam surface on said plate, and a cam surface on said body for cooperation with said plate cam surface, the said plate means acting, when pressure is applied, to move transversely inwardly of the body and through the transverse slot of the body to rotate a pin about its head as an axis from the feed position to the ejection position, the inward movement of said plate means being influenced by said cooperating cam surfaces to force the plate means downwardly of the body so that in the ejection position a pin will be firmly held between the plate means and the circular portion of the longitudinal slot and the lower wall of the transverse slot.

11. A pin holder for use in basting and other pinning operations comprising a body having a slot with a circular bottom portion extending longitudinally from one end thereof through the body and connecting to a transverse slot adjacent the other end of the body said transverse slot having a lower wall, the longitudinal slot being adapted to hold a plurality of headed pins in side-by-side relationship, resilient means attached to the body to move said pins along said longitudinal slot to said transverse slot in the body, a resilient plate attached to said body for relative movement thereto in a plane transverse to the plane of the longitudinal slot in the body, a depending ejecting member integral with said plate and extending into said transverse slot in the body, a cam surface on said ejecting member, and a cam surface on the body at the entrance to said transverse slot, said plate member acting when under pressure to move said integral ejecting member in said transverse slot to rotate a pin about its head as an axis from the feed position to the ejection position, and acting under the influence of said cooperating cam surfaces to cause said ejecting member to move downwardly and to firmly engage and hold the pin in the ejection position in cooperation with the circular portion of the longitudinal slot and the lower wall portion of the transverse slot.
